CIRCULAR KNITTING MACHINE HAVING A LATCH LIFTER AND METHOD OF OPER- ATING SAME

Grover C. Parham, Dalton, Ga., assignor to Scott
& Williams, Incorporated, Laconia, N. H., a
corporation of Massachusetts

Application March 28, 1950, Serial No. 152,340

16 Claims. (Cl. 66—111)

1

This invention relates to a circular knitting machine having a latch lifter, and to a method of operating same, and more particularly to a latch lifter adapted to assist the casting off of transferred loops. In making ladies' hosiery on automatic circular knitting machines that have independent latch needles, it is desirable to make a turned welt. For this purpose transfer bits are used to take loops at the beginning of the knitting and to transfer them back to the needles after the welt has been knitted. When these loops have been transferred back to the needles preparatory to knitting them into the fabric, they lie loosely around the needle shanks and are so slack that they sometimes get caught on the ends of the latches and get into the hooks of the needles instead of being cast off with the old stitch. When this happens the loops are not cast off until a subsequent revolution of the machine. This produces an irregular and undesirable appearance to the welt. One of the objects of the present invention is to prevent the formation of such a ragged-appearing welt in circular knit stockings. Another object is to prevent a needle latch from becoming caught in any loop on a needle shank.

It is characteristic of a machine made in accordance with my invention that the latch lifting blade functions at a point spaced from the stitch cam. I have found that if the latches are lifted part way by the blade as soon as the welt loops are transferred to the needle shanks, the centrifugal force created by the rotary movement of the needle cylinder in the modern automatic hosiery knitting machine will prevent the latches from dropping down again when they get beyond the lifter blade. For this reason the end of the blade is located some distance from the casting off point of the stitches:

In the drawings:

Figure 1 is a perspective skeleton view of the top of a needle circle, sinker cap and associated parts of a Scott & Williams independent latch needle circular knitting machine made in accordance with my invention, showing the latch lifter blade in operation;

Figure 2 is a perspective view of a few needles and fabric loops seen from the center of the dial of Fig. 1, showing the effect of the latch lifter blade on the latches of the needles and its relation to the slack transferred loops;

Figure 3 is a partially developed view from the outside of the needle cylinder, diagramming the needles and some of their operating cams, the transfer bits and the latch lifter at those points of the operation where the welt loops are being transferred back to the needles and where the latch lifter is raising the latches from their fully-open position;

Figure 4 is a view of the transfer line of a welt made according to the prior art; while

2

Figure 5 is a similar view of a welt transfer line made in accordance with my invention.

The invention will be shown and described in the well-known Scott & Williams automatic latch needle circular knitting machine adapted to make ladies' hosiery with automatic inturned welt, but it should be understood that the invention may also be used in any other type of revolving needle cylinder circular machines. For an example of a Scott & Williams machine adapted to make such ladies' hosiery with automatic inturned welt, reference is made to the Robert W. Scott U. S. Patent No. 1,282,958, dated October 29, 1918. In the machine shown in the drawings of the present application there is the usual needle cylinder containing a circle of independent latch needles N, N' having latches 21. The needle cylinder is of the rotary type and has the usual stationary knitting cam cylinder surrounding it. Intercalated with the needles are the usual sinkers S actuated by the outside sinker cap 300. The machine also contains the usual stitch cams 360, 361 and top center cam 357.

The sinker cap rests on the upper end of the needle cylinder but is restrained from rotating. When the needle cylinder starts to move in the reverse direction during reciprocatory knitting, the sinker cap makes a short oscillatory stroke governed by the so-called down-pick post 401 shown at the left of Fig. 1. My novel latch lifter is pivotally mounted on the sinker cap in the embodiment shown in the drawings, but it should be understood that basically my invention can also be carried out by mounting the latch lifter on a stationary part of the machine.

As shown in the above-mentioned Scott Patent 1,282,958, there is a dial D containing a transfer bit T corresponding to every other needle in the cylinder. When the transfer needles N have been drawn down below the level of the transfer bits at the end of the making of the welt by a cam 1 shown at the left of Fig. 3, the transfer bits are projected outwardly between the still elevated non-transfer needles N'. In this position the eyes 3 of the transfer bits are over the transfer needles N to which the loops are to be transferred. The needles N then are raised through the eyes 3 by a cam surface 2 till the needle latches are above the bits. Shortly after the lower end of the latch of each needle has cleared above its transfer bit, the bit is retracted, leaving the loop on the shank of the needle. This is the situation at the point marked 4 in Fig. 3.

These loops are transferred onto the needles at a point about 90° in advance of the knitting or cast off point 1. Experience shows that some of the loops tend to ride over the ends of the latches. When this occurs and the latch subsequently closes as the regular tight loop on the

needle shank rides up, the slack transferred loop gets under the hook of the needle and is not cast off. On the next revolution of the machine this slack loop is again cleared below the latch and unless it happens to ride over the end of the latch a second time, the needle will cast the loop off one course later than usual. The result of this irregular casting off is to produce the ragged appearance shown in Fig. 4. I have found means by which this irregularity can be completely eliminated, giving the uniform appearance to the welt shown in Fig. 5.

I provide a latch lifter located shortly after the point 4 at which the transfer bits retract, leaving the slack transfer loops on the needles. My latch lifter is not intended to completely close the latch because the latch must be left open until shortly before the stitch cam in order that a new yarn may be laid under the hook of the needle. On the other hand, it will be observed that the danger of the slack loop catching on the latch begins as soon as the needle starts to lower. My latch lifter plays a vital part in raising the latch from its downward, fully-open position to a partially-closed position in the general neighborhood of a horizontal direction in the case of vertically movable needles. I also take advantage of centrifugal force. In automatic circular hosiery knitting machines when knitting in a rotary manner the needle cylinder turns so fast that I find a latch which has been partly raised will not return to its fully-open position. On the other hand, I have noticed that, perhaps due to surface tension of oil, centrifugal force is often not enough to bring the latch upward from its fully-open position after it is freed from the stitch. Therefore my latch lifter is needed to start the movement. I find that centrifugal force is ample to overcome any tendency of the latch to drop back to fully-open position under the action of gravity after it has been partly raised by my lifter. In fact, centrifugal force, once started, tends to open the latch even further. I have found that with my lifter all the latches will surely pass above all the loose or slack transferred loops and thus avoid the undesirable appearance shown in Fig. 4.

In the embodiment shown in the drawings I have provided a circumferentially stationary lifter blade 10 and I have used descent of the needles from the clear level 8 to an intermediate level 9 to cause the latches to engage the lifter and partially raise the latches. Thus in the drawings it will be seen from Figs. 2 and 3 that it is the descent of the needles N, N' from the clear level 8 to the intermediate level 9 which brings the needles into contact with the latch lifter blade. It will be noted that the upper edge 11 of the blade is preferably horizontal and that the blade has considerable vertical depth.

In view of the fact that the transferred loops are present on the shanks of the needles only at the time the welt is being completed, the latch lifter blade need be in operative relation with the needles for a very limited time. Therefore I have provided means by which this blade can be moved into and out of operative relation with the needle latches. These means are controlled from cams 161, 162 and 163 on the usual pattern drum 120 by a thrust rod 462. This thrust rod conveniently can control not only the latch closing means but also the transfer bits. The lifter blade itself is fixed in a plate 14 mounted

on the upper face of the usual sinker cap 300 by a screw 15. This is a pivotal mounting such that the end of the blade can be swung into and out of contact with the needles at the proper time. Projecting from this plate is a wire tail 16 which extends from the plate at an angle of say 90° from the latch lifter blade. There is a tension spring 17 attached to this tail, the other end of this spring being fastened on the sinker cap 300. The tension spring extends in such a direction as to pull the latch lifter blade into its operative position under the latches. While the spring and tail thus tend to pull the blade into its operative position, the thrust rod 462, by means of a camming finger 463 on it, normally pushes on the wire tail 16 against the tension spring 17 and thus holds the blade away from the needle cylinder and the needles. This finger 463 holds the blade out in this manner whenever the thrust rod 462 is down in its lowermost position on the pattern drum 120. It will be seen from Figs. 1 and 3 that as soon as the thrust rod rides up on drum cam 161, the cam surface of the finger 463 releases the wire tail 16 and the tension spring 17 will pull the latch lifter blade into its operative position. The higher drum cam 162 raising the thrust rod further will have no effect on the latch lifter blade because such raising of the thrust rod merely increases the separation between the wire tail and the finger 463. The adjustment of the machine is such that the thrust rod 462, moving in to begin the operation of transferring the loops 12 to the needles, allows the latch lifter blade to move to its operative position before any needles having transferred loops on them arrive opposite the blade. The means which project the transfer bits over the transfer needles N are active for at least one and a half revolutions, and it will therefore be obvious that the latch lifter blade will be in its operative position until after all the loops transferred to the transfer needles N have passed the point where their latches can be affected by the blade.

It will be noted that in Fig. 2 I have shown only one latch at a time being raised by the latch-lifter blade. I have found that this aids in inserting the blade in its operative position. It will be understood, of course, that other types of blades might be used without departing from the broad aspects of my invention. It will be noticed in the drawings that there is a considerable distance between the end of the latch-lifter blade and the point where the needles begin to descend the stitch cam.

This point where the latch lifter blade ends is indicated in Fig. 3 by the reference character 5. The point at which the stitch cam begins to act on the needles is indicated by the reference numeral 6, and the casting-off point is indicated by the reference character 1. It will be obvious that by means of my invention the latches are kept from their fully-open position at the point 5 by means of the latch lifter blade. Thereafter until after the needles have passed point 6 they continue to be held up from their lowermost position and out of danger from contact with the slack loops by centrifugal force.

When the thrust rod 462 off its cams at the end of the transfer operation, the camming surface of the finger 463 will push on the wire tail 16, causing the latch lifter blade 10 to be swung radially outward away from the needles and needle cylinder.

In circular knitting machines the sinker cap

306 has an oscillatory movement when knitting heel and toe pockets. During rotary knitting the sinker cap is held in one extreme of its oscillation by the usual down-pick post 401 (see Fig. 1). But each time the machine starts to knit in the reverse direction (clockwise as it appears in Fig. 1), the cap has a limited radial movement. The pivot screw 15 of the plate 14 carrying the latch lifter blade is so located with respect to the forward knitting cams of the needles and the thrust rod 462 that the interaction of blade and needle latches heretofore described is effective when the sinker cap is turning in its forward direction but not in its reverse direction. While the sinker cap is making its limited oscillation on a reverse movement of the needle cylinder, the wire tail 16 is a short distance away from the camming surface of the finger 463. The spring 17 therefore holds the latch lifter blade in its operative position. There is danger, as the sinker cap approaches the end of its reverse movement, that the latch lifter blade will come in damaging contact with the needles and break them. To avoid this danger, I provide an element on a stationary part of the machine adapted to push on the plate 14 to move the blade out of action. This element is a finger 18 mounted on the dial driving shaft post 19 carrying the dial drive gear. The finger is stationary. As soon as the sinker cap returns to its rotary or forward position, the plate and blade will be released from this finger to the control of the thrust rod 462. It will be obvious that, if desired, I can mount the plate and blade on a stationary part of the machine.

I also find it convenient to provide a short control finger 20 on the plate so that the latch lifter blade can be swung out of operative position by hand.

It will be seen that the wire tail 16 and camming finger 463 keep the blade out of action during rotary knitting except just prior to, during and immediately following loop transfer, and that the finger 18 on the stationary part of the machine holds the latch lifter blade out of action during knitting in the reverse direction. These two means cooperate so that one is effective during knitting in the forward direction and the other during knitting in the reverse direction, each releasing control to the other at the proper time.

While the invention is peculiarly useful in connection with transferred stitches, it will be obvious that partial closing of the latches and maintaining them partially raised by centrifugal force, can also be used in non-transfer knitting.

I claim:

1. An automatic stocking knitting machine having a rotary circle of independent needles with pivoted latches and a stitch cam for casting loops off the needles, in combination with latch lifting means comprising a blade adapted to be moved to and from an operative position at or near the shanks of the needles to raise latches to a position not substantially above the horizontal position and only partially toward closed position during and after the transfer, and means to control the position of the latch lifting means.

2. A circular stocking knitting machine according to claim 1 in which the blade when in its operative relation with the needle latches is adapted to engage only one or two latches at

a time, whereby the blade can be freely moved into and out of operative position under the latches.

3. A circular stocking knitting machine having a rotary circle of independent needles with pivoted latches, bits to transfer loops to the needles as the latter rise through the eyes of the bits, means to operate the bits and a stitch cam for casting loops off the needles, in combination with latch lifting means comprising a blade adapted to be moved to and from an operative position at or near the shanks of the needles to raise latches only partially toward closed position during and after the transfer, and means adapted to control both the transfer bits and the latch lifting means.

4. A circular stocking knitting machine adapted to make an automatic turned welt, said machine having a needle cylinder, a circle of independent needles and independent sinkers therein, a latch lifter blade pivotally mounted on the machine to swing toward and away from the needle cylinder, and means urging the blade toward the cylinder, in combination with a thrust rod controlling the transfer of loops at the welt, and means actuated by the thrust rod holding the blade out of action during rotary knitting except just prior to, during and immediately following welt transfer.

5. A circular stocking knitting machine adapted to make an automatic turned welt, a needle cylinder having therein a circle of independent latch needles and independent sinkers and a sinker cap, latch lifting means in which there is a blade pivotally mounted on the sinker cap, a spring associated with the blade tending to push it into its operative position, a thrust rod adapted, when lowered, to hold the blade out of action, means to raise the thrust rod

40 for transferring stitches, the parts being so arranged that oscillation of the sinker cap during knitting in the reverse direction releases the tension, the latch lifter blade being pivotally mounted on the sinker cap, and the means to control the position of the latch lifting means including means tending to pivot the blade into its operative position and two means tending to pivot the blade out of its operative position, one effective for knitting in the forward direction and the other in the reverse direction, the forward means being adapted to release its control from the thrust rod, and an element on a stationary part of the machine adapted to push the blade out of action when the sinker cap is thus oscillated.

6. A circular stocking knitting machine according to claim 1 in which there is a needle cylinder containing a circle of needles adapted to turn in both the forward and reverse directions, a circle of independent sinkers in the cylinder and a sinker cap having a limited oscillatory movement on change of direction of knitting during forward knitting when loops are to be transferred.

7. An automatic circular knitting machine having a rotary circle of independent needles with pivoted latches, bits to transfer loops to the needles as the latter rise through the eyes of the bits, means to operate the bits and a stitch cam for casting loops off the needles, in combination with a latch lifter ahead of and circumferentially spaced from the stitch cam and adapted to partially raise the latches of the needles, said machine being adapted to rotate at such a speed that the latches do not drop

down after leaving the lifter, whereby the transferred loops on the shanks of the needles are prevented from getting into the hooks of the needles.

18. An automatic circular knitting machine having a rotary circle of independent needles with pivoted latches, bits adapted to transfer loops to the needles as the latter rise through the eyes of the bits, cam means adapted to lower needles to an intermediate level from a first level where the loops were transferred to the needles below the latches, and a stitch cam adapted to lower the needles from the intermediate level to cast off the loops, in combination with a latch lifter effective only during the lowering of the needles to the intermediate level to partially raise the latches to a position not substantially above horizontal position, whereby the transferred loops are prevented from getting into the hooks of the needles.

19. An automatic circular knitting machine having a rotary circle of independent needles with pivoted latches, and a stitch cam for casting loops off the needles, in combination with a latch lifter spaced some distance ahead of the stitch cam adapted to move all the fully-open latches of passing needles less than 90° toward closure; whereby any stitches on the shanks of the needles below the latches are prevented from catching on the latches while the needles are travelling from the lifter to the stitch cam and the latches are left open sufficiently to prevent interference with yarn being fed to the needles.

10. An automatic circular knitting machine having a rotary circle of independent needles with pivoted latches, a stitch cam for casting loops off the needles and a latch lifter spaced some distance ahead of the stitch cam adapted to raise the latches of passing needles less than 90° to approximately the horizontal position, said circle of needles being adapted to rotate at such a speed that the latches do not drop down after leaving the lifter; whereby any stitches on the shanks of the needles below the latches are prevented from catching on the latches while the needles are travelling from the lifter to the stitch cam and the latches are left sufficiently open to prevent interference with yarn being fed to the needles.

11. An automatic circular knitting machine having a rotary circle of independent needles with pivoted latches, a stitch cam for casting loops off the needles and a cam spaced some distance ahead of the stitch cam adapted to move needles vertically, in combination with a latch lifter also spaced some distance ahead of the stitch cam adapted to raise the latches of passing needles less than 90° toward closure as the needles leave such advance cam; whereby any stitches on the shanks of the needles below the latches are prevented from catching on the latches while the needles are travelling from the lifter to the stitch cam and the latches are left sufficiently open to prevent interference with yarn being fed to the needles.

12. An automatic circular knitting machine having a rotary circle of independent needles with pivoted latches, and a stitch cam for casting loops off the needles, in combination with a latch lifter spaced some distance ahead of the stitch cam adapted to raise the latches of passing needles less than 90° and release them near the horizontal position, said latch lifter also being adapted to keep under it any loops on the shanks of passing needles, and means adapted to

move the lifter automatically into and out of operative relation with the needle latches; whereby any loops transferred to the shanks of the needles in advance of the stitch cam are prevented from getting into the needle hooks.

13. A method of operating an automatic circular knitting machine having a rotating circle of latch needles, a stitch cam and a latch lifter, in which there are at least the step of lifting the needle latches less than 90° to partially closed position by means of the lifter and the step of rotating the needles in the needle circle for a distance after leaving the lifter and before reaching the stitch cam and during that distance preventing the latches from returning to fully-open position by centrifugal force, and thereafter casting off loops on the needle shanks by means of the stitch cam, whereby the loops on the needle shanks are prevented from getting into the hooks of the needles.

14. A method of operating an automatic circular knitting machine having latch needles, a latch lifter and transfer bits, in which there are at least the steps of transferring loops from the bits to the needles below the latches while the latches are open, lowering the needles having the transferred loops to an intermediate level while simultaneously positively lifting the latches part way from their fully-open position by means of the lowering and the latch lifter, and thereafter rotating the machine at such a speed that the latches are prevented by centrifugal force from returning to fully-open position and thereafter lowering the needles further to cast off the loops, whereby the transferred loops do not get caught under the hooks of the needles.

15. A method of transferring loops on an automatic circular knitting machine having independent latch needles, a latch lifter and transfer bits comprising the steps of transferring loops from the bits to the needles, raising the needles to clear level, then lowering them to an intermediate level which simultaneously positively lifting up the latches part way on the latch lifter, allowing the needles to travel at that intermediate level, and thereafter feeding yarn and drawing the needles down a stitch cam to cast off the transferred loops and draw new loops, whereby the slack transferred loops do not get caught in the hooks of the needles.

16. A method of transferring loops on an automatic circular knitting machine according to claim 15 in which after the latches are raised up part way the needles continue at that intermediate level for a time beyond the latch lifter with the latches held up by centrifugal force before the needles go down the stitch cam, whereby the latches remain above the reach of the slack loops for the entire period from transfer to stitch cam.
